ATTACHMENT FOR PRINTING PRESSES

Dewey Fickes, Shippensburg, Pa., assignor to
The Beistle Company, Shippensburg, Pa., a
corporation of Pennsylvania

Application May 23, 1934, Serial No. 727,183

4 Claims. (Cl. 34—18)

The object of this invention is to provide an attachment for printing presses by the use of which offsetting in the printed sheets and static electricity in the pile of printed sheets will be eliminated. The invention seeks to provide a device for the stated purpose which may be readily mounted upon the delivery end of a printing press and furnish heat to play directly upon the printed sheets after they are delivered so that the ink will be thoroughly dried and the presence of static electricity will be overcome. Other objects of the invention will appear incidentally in the course of the following description and the invention resides in certain novel features which will be particularly pointed out in the appended claims.

In the annexed drawings:

Figure 1 is a perspective view of the delivery end of a printing press showing my attachment in position thereon.

Figure 2 is a longitudinal section through one of the burners.

Figure 3 is a transverse section on the line 3—3 of Figure 2.

Figure 4 is a perspective view of the attachment removed from the press.

Figure 5 is a transverse section on the line 5—5 of Figure 2.

In the drawings, the reference numeral 1 designates generally the sheet delivery mechanism of a printing press, the numeral 2 designates the table upon which the printed sheets are piled, and 3 designates the printed sheets upon the table. In carrying out the present invention, there is provided a heater which is indicated generally by the numeral 4 and which is disposed between the sides of the sheet delivery mechanism, as clearly shown in Figure 1. This attachment comprises a header 5 having a central notch 6 extending upwardly from its lower edge and having a nipple 7 formed thereon to receive one end of a gas supply pipe 8 which is equipped with a cut-off or regulating valve 9 and may be connected through a hose or other flexible pipe 10 with any convenient source of gas supply. In each of which there is secured one end of a burner tube 12, the opposite end of the burner tube being, of course, closed. In the present instance, the closures for the ends of the burner tubes are in the form of caps 13 which have threaded engagement with the burner tubes and are also provided with threaded sockets on their outer sides to receive securing screws 14 which are fitted through bosses 15 on the end wall 16 of the heater. This arrangement firmly supports the ends of the burner tubes and also provides for effectual closing of the same, although, if repairs or renewals should be necessary, the tubes may be very easily released and withdrawn.

The end wall 16 is flared downwardly and outwardly, as clearly shown in Figure 2, so that the heat may spread as it passes through the open bottom of the heater and, therefore, play upon the entire area of the printed sheets which are being delivered. The end wall 16 is somewhat lighter than the header 5 but is of the same general form, having a notch 17 extending upwardly from its lower edge. The header and the end wall are each provided or formed with a lug 18 extending from the upper wall of the respective notches 6 and 17 through which bolts or similar fastenings may be inserted to secure the attachment upon a cross bar 19 of the frame of the printing press so that the attachment will be supported in the desired location. A central chamber or space is thus provided in the heater through which air may rise and inner walls or partitions 20 extend longitudinally of the heater between the header 5 and the end wall 16 so as to prevent spreading of the heat from the burners into the central space and clearly define said space so that there will be an ample circulation of cool air to prevent the parts of the press, adjacent the heater, being raised in temperature to an undesirable degree. In order that the temperature in this central space may be kept low, the longitudinal inner walls or partitions 20 are provided with linings 21 of asbestos or other heat-resisting material, which linings are secured against the partitions by clamping plates 22 in an obvious manner. Secured upon the upper edges of the header 5 and the end wall 16 and extending between the same are covers 23 which, as shown most clearly in Figures 3, 4 and 5, are of arcuate formation with their inner edges spaced apart to provide an outlet for the partly heated air between the two branches of the heater. A burner tube 12 is disposed in each branch of the heater, and, as shown in Figures 2, 3 and 5, is located close to the bottom or lower edge of the header and the end wall thereby providing an ample space above and around the burner for the circulation of the burning gases. The burner tubes are provided with perforations or jet openings 24 which extend from end to end of the tubes and are staggered in the respective tubes so as to provide for a wide diffusion of the heat. Pilot tubes 25 extend from the gas supply pipe, at a point between the main supply and valve 9, 55

and extend to and through the partitions or walls 20 and terminate immediately adjacent the respective burner tubes so that a pilot light will be constantly burning and the gas immediately ignited when the valve is opened to permit a full flow of gas to the burner tubes.

From the foregoing description, taken in connection with the accompanying drawings, it will be seen that I have provided a very simple attachment which may be readily secured in place upon a printing press and easily removed therefrom when desired. The header 5 will deliver the gas to the two burner tubes equally so that the heat will be supplied through the entire extent of the burner and will play directly upon the printed sheets as they are brought under the attachment by the delivery mechanism. The heat will be directed through the open bottom of the heater inasmuch as its upward escape is prevented by the cover plates 23 and an accumulation of hot air which will raise the temperature of the adjacent parts of the printing press to an undesirable degree is thereby avoided. Any heated air which may tend to accumulate between the longitudinal inner walls 20 will readily escape through the open space between the upper portions of said walls. Inasmuch as the printed sheets are caused to travel directly below the heater, the hot air will play directly upon the entire surface of each sheet and will, consequently, thoroughly and quickly dry the ink which is applied to the sheets so that offsetting upon the sheets will be thoroughly eliminated and prevented. A thin film of hot air will be placed between the sheets to eliminate static electricity in the pile of printed sheets. The device will require no attention upon the part of the pressman except to open and close the regulating valve as the operation of the press is to be started or stopped.

Having thus described the invention, I claim:

1. A device for the purpose stated comprising a header, an end wall having its lower portion downwardly flared, the header and said end wall having central notches in their lower edges 45 whereby they may be engaged over a bar of a printing press, burner tubes supported by the

header and the end wall and in communication with the interior of the header, means for supplying fuel to the header, walls extending between the header and the end wall and aligned with the side walls of the notches, and cover plates secured upon the upper edge of the header, the end wall and intermediate walls. 5

2. A device for the purpose stated comprising a header, an end wall, the header and the end wall having upwardly extending notches at the centers of their lower edges whereby they may be engaged over a bar, of a printing press, longitudinal walls extending between the header and the end wall at the sides of said notches, cover plates secured upon the upper edges of the header, 15 the end wall and the longitudinal walls whereby two parallel chambers having open bottoms are defined, means for supplying fuel to the header, and burner tubes communicating with the header and supported by the same and the end wall 20 at the bottoms of the parallel chambers.

3. An attachment for printing presses including a header, a pipe for supplying fuel to the header, burner tubes in the header and extending therefrom, an end wall for supporting the 25 ends of the header tubes remote from the burner, partitions between the burner tubes and extending from the header to said tube supports, and cover plates mounted on the corresponding upper edges of the header and said supports, corresponding cover plates and partitions being spaced to permit circulation of air.

4. In an attachment for printing presses, a header having independent compartments defining an intermediate air passage opening 35 through the top thereof, burner tubes disposed within the compartments, square supports for the ends of the burner tubes remote from the header, means for supplying fuel to the burner tubes, means for controlling the flow of fuel to 40 said tubes, means in the intermediate air passage for securing the header in position on a printing press, and a cover plate for each of the compartments for limiting diffusion of heat from the attachment. 45

DEWEY FICKES.
